US00D823887S

(12) **United States Design Patent** (10) **Patent No.:** **US D823,887 S**
Jeffrey et al. (45) **Date of Patent:** **** Jul. 24, 2018**

(54) **COMPUTER DISPLAY PANEL WITH GRAPHICAL USER INTERFACE FOR A MORTGAGE APPLICATION**

(71) Applicant: **PROMONTECH LLC**, Denver, CO (US)

(72) Inventors: **Morgan Jeffrey**, Englewood, CO (US); **Laureen Harris**, Denver, CO (US); **Rahul B. Lad**, Edison, NJ (US)

(73) Assignee: **PROMONTECH LLC**, Denver, CO (US)

(**) Term: **15 Years**

(21) Appl. No.: **29/602,529**

(22) Filed: **May 1, 2017**

(51) **LOC (11) Cl. 14-04**

(52) **U.S. Cl.**

USPC **D14/487**; D14/491; D14/494; D14/489
